UNITED STATES PATENT OFFICE.

JAMES JASPER PHILLIPS, OF BROOKHAVEN, MISSISSIPPI

SCREENING APPARATUS.

1,137,526.

Specification of Letters Patent. Patented Apr. 27, 1915.

Application filed April 24, 1914. Serial No. 834,142.

To all whom it may concern:

Be it known that J. JAMES J. PHILLIPS, a citizen of the United States, and a resident of Brookhaven, in the county of Lincoln and 5 State of Mississippi, have invented a new and Improved Screening Apparatus, of which the following is a full, clear, and exact description.

The object of the invention is to provide 10 a new and improved screening apparatus, more especially designed for screening clay and like material and arranged to separate the finer particles from the coarser ones and deliver the same to different chutes so 15 that the finer particles pass directly to the brickmaking machine while the coarser particles pass to the dry pan to be treated further.

In order to accomplish the desired result 20 use is made of an inclined screen provided with a bottom, a screening plate located a distance from the said bottom to form a chute under the screening plate for receiving the fine particles that pass through the 25 screening plate, and an adjustable heater located directly under the said screening plate to heat the material passing over the screening plate and also the fine material passing through the screening plate.

30 A practical embodiment of the invention is represented in the accompanying drawings forming a part of this specification, in which similar characters of reference indicate corresponding parts in all the views.

35 Figure 1 is a plan view of the screening apparatus; Fig. 2 is a plan view of the heater in the screen; Fig. 3 is a cross section of the screen and heater, the section being on the line 3—3 of Fig. 1; Fig. 4 is a sectional 40 side elevation of the screening apparatus; Fig. 5 is a cross section of the delivery chute, the section being on the line 5—5 of Fig. 4; Fig. 6 is a similar view of the same on the line 6—6 of Fig. 4; and Fig. 7 is an 45 enlarged cross section of part of the screen and heater.

The clay or other material to be treated is elevated by a suitable bucket elevator A and finally discharged onto an inclined delivery chute B which in turn discharges onto an inclined screen C, the lower end of which connects with two receiving chutes D and E, of which the chute D receives the fine screened material from the screen C and 55 delivers it to a brickmaking machine, while the coarser non-screened material passes into

the chute E and is delivered by the latter to a dry pan for further treatment.

The delivery chute B is provided between its ends with a clod breaker F in the form 60 of iron bars extending transversely from one side of the chute B to the other side thereof, the lower edge of the clod breaker F being a distance from the bottom of the chute B so that the finer material delivered 65 by the elevator A into the chute B can readily pass down the same under the clod breaker F while the lumps strike the clod breaker F and are broken up into small pieces to pass down the delivery chute B. 70 The lower end of the delivery chute B is provided with a vertically disposed screen G to break up the material as much as possible, the screen G being preferably pivoted at its upper end so as to swing open to allow 75 all the material to pass out of the delivery chute B onto the upper end of the screen C.

The screen C is provided with a screen frame having sides C', a bottom C², and ledges C³ a distance above the bottom C² and 80 extending along the sides C' of the screen frame. The ledges C³ support a screening plate H of a suitable mesh so that the material delivered by the chute B onto the screening plate H is separated so that the finer 85 particles pass through the perforations of the screening plate H onto the bottom C² to finally reach the chute D, while the larger particles pass down the screening plate H and finally reach the chute E. 90

In order to reduce the material in its passage down the screening plate H use is made of heat supplied by a heater I in the form of a coil of steam pipes extending under the screening plate H and supported from the 95 same by cross bars J and bolts J' attached to the screening plate H, as plainly indicated in Figs. 3 and 7. By supporting the heater I from the screening plate H by means of the bars J and bolts J', the heater 100 can be adjusted closer to or farther from the screening plate to increase or decrease the heat according to the nature of the clay being treated. One end of the steam pipe coil is connected with a boiler or other suitable source of steam supply, and the other end is connected with a steam trap I' or similar device. The ends of each return bend of the steam pipe coil is provided with a drain cock I² for discharging any 105 water of condensation that may accumulate 110 in the coil.

In order to retard the material in its downward course over the screening plate H use is made of retarding means K, preferably in the form of aprons made of canvas or other suitable material, and attached to cross bars C⁴ extending between the sides C' at the upper edges thereof, as plainly indicated in Fig. 4. The aprons K hang downward so that their free ends overlie the upper surface of the screening plate H to cause the material to pass under the said aprons K and thus cause the same to be retarded with a view to insure proper screening of the material.

It is understood that the screening plate H has to be quite hot in order that the clay will readily break up into small particles to readily sift through the perforations in the screening plate H to pass down the bottom C² into the chute D and to the brick-making machine. The coarsest materials that do not pass through the perforations in the screening plate H pass down into the chute E and finally into a dry pan to be reground. It is further understood that in order to make a first class face brick the clay must have a certain percentage of moisture and be well pulverized, and as different clays contain different amounts of moisture the heat must be varied according to the clays under treatment, in order that only the requisite amount of moisture will be removed to permit it to be properly pulverized. By the use of the adjustable heater I the surplus moisture in the clay is evapo-

rated and thus allows the use of a very fine mesh screen at the same time permitting the screening of a large quantity of clay in a comparatively short time. It will also be noticed that by the use of the heater I the clay is not liable to adhere to the screen especially in damp weather.

Having thus described my invention, I claim as new and desire to secure by Letters Patent:

1. A clay screen, comprising a metal plate apertured to form a screen, a coil of longitudinally extending steam pipes on the underside of the screening plate, transverse bars upon which the coil rests, and bolts passing through the said plate and bars and provided with nuts on their lower ends.

2. In a clay screen, an inclined frame having longitudinally extending ledges on the inner faces of its sides, said ledges gradually increasing in distance from the bottom of the frame from the upper to the lower end of the frame, a metal plate apertured to form a screen and resting upon the ledges, a steam coil below the plate, means for supporting the coil from said plate, and vertical chutes arranged side by side at the lower end of the frame.

In testimony whereof I have signed my name to this specification in the presence of two subscribing witnesses.

JAMES JASPER PHILLIPS.
